TELEVISION ANTENNA

Willis E. Butts, Sr., Blissfield, Mich.

Application April 24, 1959, Serial No. 55,641

Term of patent 14 years

(Cl. D26—14)

FIG. 1.

FIG. 2.

FIG. 3.

FIG. 4.

Figure 1 is a plan view, as viewed from above, of a television antenna, according to the present invention, showing my new design.

Figure 2 is an elevational view,

Figure 3 is a view in section as viewed on line 3—3 of Figure 1, and

Figure 4 is a plan view, as viewed from below.

The dominant features of my design are shown in solid lines.

I claim:

The ornamental design for a television antenna, as shown and described.
